UNITED STATES PATENT OFFICE

150,460

DESIGN FOR A PORT LEG FLANGE

Edmund T. Price, San Diego, Calif., assignor to
Solar Aircraft Company, San Diego, Calif., a
corporation of California

Application September 21, 1946, Serial No. 133,480

Term of patent 14 years

(Cl. D54—7)

To all whom it may concern:

Be it known that Edmund T. Price, a citizen of the United States, residing at San Diego, California, in the county of San Diego and State of California, has invented a new, original, and ornamental Design for a Port Leg Flange, of which the following is a specification, reference being had to the accompanying drawing, forming a part thereof.

In the drawing:

Fig. 1 is an end elevational view of a port leg flange showing my new design;

Fig. 2 is a side view; and

Fig. 3 is a perspective view.

I claim:

The ornamental design for a port leg flange, as shown.

EDMUND T. PRICE.
